US0D1111012S

(12) **United States Design Patent** (10) Patent No.: **US D1,111,012 S**
(45) Date of Patent: ** Feb. 3, 2026

(54) **TABLET COMPUTER**

(71) Applicant: **Shenzhen Xingtong Technology Co., Ltd.**, Shenzhen (CN)

(72) Inventors: **Xiong Zeng**, Guangdong (CN); **Xinbing Li**, Guangdong (CN)

(**) Term: **15 Years**

(21) Appl. No.: **35/523,695**

(22) Filed: **Dec. 23, 2024**

(80) **Hague Agreement Data**

Int. Filing Date: **Dec. 23, 2024**

Int. Reg. No.: **DM/243324**

Int. Reg. Date: **Dec. 23, 2024**

Int. Reg. Pub. Date: **Jan. 24, 2025**

(30) **Foreign Application Priority Data**

Aug. 15, 2024 (CN) 202430516990.9

(51) **LOC (15) Cl.** **14-02**
